(57) **CLAIM**

The ornamental design for a marker pen having casing made of transparent material, as shown and described.

DESCRIPTION

FIG. 1 is a top left perspective view of a marker pen having casing made of transparent material showing my new design;

FIG. 2 is a top right perspective view;

FIG. 3 is a top plan view;

FIG. 4 is a bottom plan view;

FIG. 5 is front elevational view;

FIG. 6 is a rear elevational view;

FIG. 7 is a right side elevational view;

FIG. 8 is a left side elevational view;

FIG. 9 is a top left perspective view in an exploded condition;

FIG. 10 is a top right perspective view of FIG. 9;

FIG. 11 is a top plan view of FIG. 9;

FIG. 12 is a bottom plan view of FIG. 9;

FIG. 13 is a front elevational view of FIG. 9;

FIG. 14 is a rear elevational view of FIG. 9;

FIG. 15 is a right side elevational view of FIG. 9; and,

FIG. 16 is a left side elevational view of FIG. 9.

UNITED STATES PATENT AND TRADEMARK OFFICE
CERTIFICATE OF CORRECTION

PATENT NO. : Des. 460,484 S
DATED : July 16, 2002
INVENTOR(S) : Michael Louis Bianco, Jr.

Page 1 of 16

It is certified that error appears in the above-identified patent and that said Letters Patent is hereby corrected as shown below:

The title page showing an illustrative figure, should be deleted and substitute therefor the attached title page.

Delete Drawings Figs. 1-16, and substitute therefore the drawings, consisting of Figures 1-16, as shown on the attached pages.

Signed and Sealed this

Seventeenth Day of August, 2004

A handwritten signature in black ink, reading "Jon W. Dudas", is placed within a rectangular box with a dotted grid background.

JON W. DUDAS
Acting Director of the United States Patent and Trademark Office
